FRANK MASTRANGELO AND ALPHONSO MASTRANGELO, OF FITCHBURG,
MASSACHUSETTS

MILK-BOTTLE-RECEIVING CABINET

Application filed March 9, 1929. Serial No. 345,838.

This invention relates to a device adapted to be built into the wall of a building by which milk or any other commodity can be left in a compartment by the deliverer and kept there until taken out by the housekeeper from the inside.

The principal objects of the invention are to provide a compartment, built in as specified, which will be readily accessible to a delivery man for depositing articles, groceries, but especially milk, and will be easily locked by him so that it cannot be again reached from the outside; and to provide an arrangement whereby when the articles are taken out from this compartment through the inside wall the outside will be left unlocked so that it will be accessible for delivery again, either that day or the next.

The invention also involves other features of construction and other objects as will appear.

Reference is to be had to the accompanying drawings, in which

Fig. 1 is a view of the outside of a building showing a structure constructed for the purpose set forth herein;

Fig. 2 is a sectional view of the same on the line 2—2 of Fig. 1;

Fig. 3 is a sectional view on the line 3—3 of Fig. 2;

Fig. 4 is an enlarged sectional view like a part of Fig. 2, showing the details of the locking and holding mechanism in unlocked condition;

Fig. 5 is a similar view showing the parts in locked condition; and

Fig. 6 is a sectional view on the line 6—6 of Fig. 5.

Although this invention is capable of general use for the delivery of any article, particularly groceries, it is designed especially for use for the delivery of milk. Milk has to be delivered in many places at an early hour and is left out in the sun, and also if not well sealed, is exposed to the wind, rain and dust and is likely to become contaminated.

This invention is designed to provide a panel built into the wall of a house with a compartment in which the milk bottles can be deposited from the outside and can be so

left that thereafter this compartment cannot be opened from the outside but only from the inside. It is constructed so that when the bottles are removed from the compartment through the inside wall of the house the 55 compartment will naturally be left unlatched so that the next day, or at any time later, it can be opened from the outside for the delivery of other bottles or articles. In fact it has to be left in that condition and as long as 60 it is in working order it cannot accidentally be left locked by the person removing the bottles into the house.

As stated, the device is built into the house and we have shown two uprights 10 which are 65 intended to represent the usual uprights without any special fitting, and it is between these that the device is intended to be supported. It comprises a rectangular frame 11 consisting of top and side pieces fitting between 70 the two uprights 10 and also between a pair of cross pieces 12, if so desired, and secured to the uprights especially. This frame 11 obviously furnishes a space which otherwise will be taken up by the external wall of the house. 75 It is provided with finish 13 on the inside and outside such as is used for door casings and the like, and in fact on each side this constitutes a door casing. A vertical outside door 14 is provided in the outside of the casing 13 80 and an inside door 15 in the inside in the same way.

Accordingly it will be seen that the whole device is so constructed as to present no appearance that would detract from that of the house either on the inside or outside, but is rather ornamental if anything. An ordinary latch 16 is shown for the outer door which can be opened by anybody and is never intended to be locked. The inside door can be 90 unlatched in a similar way or merely have a knob for operating it.

A board or plate 17 is located on the outside of the frame 11 across the bottom constituting a partition from one edge to the other 95 and of a height at least as great as that of the tallest milk bottle or other article which the device is intended to be used for. On the horizontal top of the partition 17 are placed hinges 18 and a horizontal door 19 is se- 100

cured to the hinges so that it can be raised at least part way up about these hinges, as shown in dotted lines in Fig. 4. The handle 20 is used for raising it.

5 It will be seen that when the door 14 is opened the delivery man can reach into the upper part of the frame 11 which is hollow and grasp the handle 20 and raise the door 19 and put in the milk over and behind it. The 10 partition 17 seals the space behind it against theft from that part of the door opening at the outside.

The door 19 is intended to be left in an unlocked condition until the milk is deposited 15 and then positively locked. For this purpose it is provided with an ordinary spring latch 21 and the inner door 15 is provided with a slot 22 for receiving this latch. Also 20 on the side walls of the frame 11 are a pair of springs 23 which are easily secured to the side walls and easily removed for repairs. These springs set into notches 24 in the frame 11 and are bent back from the point of attachment and then inwardly and preferably 25 on a slant to form a slanting support 25 at the end thereof. The door 19 is adapted to rest on these springs in the position shown in Fig. 4 with the spring latch above the notch 22.

In operation both doors are normally 30 closed and the parts are in the position shown in Fig. 4 with the spring latch 21 held up above the top of the notch 22 by the springs 25. As there is nothing in the lower compartment there is no objection to having the 35 door 14 unlocked and, as stated, it is merely latched by the outside latch. The milk man opens this door 14 and reaches in for the handle 20 and raises the door 19. Then he puts the milk over the top of this door and 40 into the compartment below it. Now he closes the door 19 and presses down on it. This results in causing the springs 25 to yield and allow the latch 21 to spring into the notch 22. This latch is held up against the top of this 45 notch by the springs 25. Therefore, it will be seen that although there is milk in this lower compartment it is absolutely locked because there is no way to get at the latch 21 and no handle is provided for it so it is immaterial that the door 14 is not locked.

50 When the housewife wishes to take the milk out she simply opens the inside door which releases the latch 21 from the notch 22 and the spring 25 raises the door 19 slightly. 55 She removes the milk and then closes the door 15. The result is that the latch 21 is pressed back a little as shown in Fig. 4, but the door 19 cannot come down and the latch 21 cannot enter the notch 22. In other words, 60 the parts are now again in the position in which we started, that is, the position shown in Fig. 4.

65 This constitutes a simple and convenient construction by which the milk man can get at the milk compartment to supply it with

bottles and by which, afterward, it is locked against access from the outside and yet when the milk is removed and the inner door closed the milk compartment is left unlocked. Nobody has to go to it again or think about it 70 any more to be sure that it is ready for the reception of milk from the outside.

Furthermore, if it is wished to use this compartment for the delivery of other articles, they can be placed on top of the door 19 or a 75 grocery man can reach in, open this door, deposit groceries in the lower compartment and then not press the door 19 down to locking position, thus permitting it to be used for two purposes and preventing its use for the 80 other purpose interfering with its use for the reception of milk bottles.

This device can be manufactured by concerns whose business it is to make builders' 85 finish, door casings, or window casings. It can be sold to be placed in any house in the process of building or, of course, if desired, afterwards. It does not have to be made in different sizes for different buildings, but is 90 made in accordance with the usual spacings of uprights. At least there are only a few ways in which they are spaced so that there can be only two or three sizes of these devices to suit practically all wooden frame buildings.

95 Although we have illustrated and described only one form of the invention we are aware of the fact that modifications can be made therein by any person skilled in the art without departing from the scope of the 100 invention as expressed in the claims.

Therefore, we do not wish to be limited in this respect, but what we do claim is:—

1. In a receptacle for articles, the combination with a frame having a vertical partition 105 along the outer side extending from the bottom part way to the top and a horizontal door pivoted to the top of said partition, of outside and inside vertical doors, each adapted to be opened from its own side, the inside door having a notch and the first named door having a spring latch adapted to engage in said notch, whereby when the horizontal and inside vertical doors are closed the horizontal door is locked if the latch is located in the notch.

110 2. In a receptacle for articles to be delivered, the combination with a frame adapted to be built into the wall of a house and having a horizontal door extending across the frame, of outside and inside vertical doors of the same size, each covering the entire surface of the frame and each adapted to be opened from its own side under all conditions, the inside door having a notch and the first named door having a spring latch adapted to engage in said notch, whereby when the two last named doors are closed the horizontal door is locked if the latch is located 115 in the notch.

3. In a receptacle for articles, the combination with a frame having a vertical partition along the outer side extending from the bottom to a point near the center, of a horizontal door pivoted to the top of said partition and extending across the frame, outside and inside vertical doors, each adapted to be opened from its own side, the inside door having a notch and the horizontal door having a spring latch adapted to engage in said notch, and yielding means on the frame for normally forcing the horizontal door up to a position in which the spring latch will not enter said notch, whereby when the inner vertical door is closed, the horizontal door may be held in unlatched position and can be opened from the outside.

4. In a device of the character described, the combination of a rectangular frame adapted to be built into the wall of a house between a pair of uprights thereof, a vertical partition at the extreme outer side of said frame extending from the bottom to a point adjacent the center and horizontal on top, a door hinged to the top of said partition and normally adapted to lie in horizontal position, said door extending clear across the frame, a vertical door covering one side of the frame and having a notch at the end of the horizontal door, a pair of springs on the frame projecting inwardly to support the horizontal door at a distance from its hinges and hold it in slightly inclined position, a spring latch on the horizontal door adapted to enter said notch when the door is pressed down in opposition to said springs, and a handle on the top of the horizontal door for operating it.

5. In a receptacle for articles, the combination with a frame having a vertical partition along the outer side extending from the bottom part way to the top and a horizontal door pivoted to the top of said partition, of an inside vertical door having a notch and the first named door having a spring latch adapted to engage in said notch, whereby when the doors are closed the horizontal door is locked if the latch is located in the notch.

In testimony whereof we have hereunto affixed our signatures.

FRANK MASTRANGELO.
ALPHONSO MASTRANGELO.
